CLAIM

The ornamental design for a display screen with graphical user interface, as shown and described.

DESCRIPTION

FIG. 1 is a front view of a first embodiment of a display screen with graphical user interface;

FIG. 2 is a front view of a second embodiment of a display screen with graphical user interface; and,

FIG. 3 is a front view of a third embodiment of a display screen with graphical user interface.

The broken lines showing a display screen, text, numbers, symbols, and portions of the interface are included for the purpose of illustrating portions of the article and forms no part of the claimed design.

1 Claim, 3 Drawing Sheets
